(57) **CLAIM**

The ornamental design for a vehicle exterior, as shown and described.

DESCRIPTION

FIG. 1 is a front perspective view of a vehicle exterior showing our new design;

FIG. 2 is a rear perspective view thereof;

FIG. 3 is a side elevational view, the opposite side being a mirror image thereof;

FIG. 4 is a front elevational view thereof;

FIG. 5 is a rear elevational view thereof; and,

FIG. 6 is a top plan view thereof.

The broken line showing of the head lamps, front parking lights, wheels and tires, rear view mirrors, door handles, portions of the door molding, tail lamps, license plate mount and two rear lights and the rear bumper element is for illustrative purposes only and forms no part of the claimed design.
